(57) **CLAIM**

The ornamental design for a dress shirt with hidden medical access points, as shown and described.

DESCRIPTION

FIG. 1 is a front, elevational view of a dress shirt with hidden medical access points, the access points located on the inside sleeve of each arm and on the upper left-side chest and upper right-side chest, each access point hidden by a closed zipper; FIG. 2 is a right perspective view of FIG. 1;

FIG. 3 is a left perspective view of FIG. 1;

FIG. 4 is a front, elevational view of the dress shirt with hidden medical access points of FIG. 1, showing each zipper in the open position to expose each access point;

FIG. 5 is a right perspective view of FIG. 4; and,

FIG. 6 is a left perspective view of FIG. 4.

The even broken lines showing stitching form part of the claimed design. The dot-dash broken lines immediately adjacent to the solid lines are boundary lines and form no part of the claimed design. The remaining dot-dash broken lines show portions of the dress shirt with hidden medical access points that form no part of the claimed design.

In the drawings, the broken lines show portions of the dress shirt with hidden medical access points that form no part of the claimed design. It will be understood that all lines in the drawings, including broken and solid lines, are intended to convey the full disclosure of the design.

1 Claim, 6 Drawing Sheets
